Cooper, Kerr & Dunham

UNITED STATES PATENT OFFICE.

SEWARD E. SWICK, OF DETROIT, MICHIGAN, ASSIGNOR TO INTERNATIONAL TIME RECORDING COMPANY OF NEW YORK, OF ENDICOTT, NEW YORK, A CORPORATION OF NEW YORK.

TIME RECORDER.

Application filed December 31, 1924. Serial No. 758,970.

This invention pertains to time recorders of the kind used by employers to record the comings and goings of their employees.

It has to do preferably but not necessarily with that type of recording clock provided with a card receptacle into which each employee inserts his own particular card and then by operating a lever causes the clock mechanism to imprint the time of day on the card. On the time recorder I have in mind all time figures are printed on the record in blue until a certain predetermined hour and minute at which time the recorder under control of the clock automatically shifts the printing ribbon which is provided with strips of two colors, so that the printing will be in red instead of blue on all records made after the predetermined time mentioned above.

In addition to the above provision it is the rule in some establishments that a late arrival be not permitted to register at all until a foreman or supervisor has been called to interview him, and my present invention provides means to insure that this rule be carried out by making it impossible to operate the recording mechanism of the clock until the foreman is present at the clock.

In every clock the recording mechanism is enclosed in a cover or case held in position by a lock to which only foremen have keys and my invention contemplates the interlocking of the recording mechanism of the clock with the ribbon shift devices in such manner that when, at the predetermined time, the ribbon shifts from blue to red, the recording mechanism will be rendered inoperative, to be made operative again only when and while the foreman's key is inserted in the above mentioned case lock and turned.

In the drawings,

Fig. 1 is a cross section of the clock case showing portions of the ribbon shift mechanism, recording mechanism and the case lock.

Fig. 2 is a front view of my locking mechanism on line 2—2 of Fig. 1.

Fig. 3 is a side view on line 3—3 of the parts shown in Fig. 2.

10 designates the cover or case enclosing the mechanism. This case is secured to base board 11 by hook 12 interlocking with piece 13 which is fastened to base board 11. Hook

12 is controlled by lock 14 and key 15 by means of which 12 may be disengaged from 13 when it is desired to remove the case. These parts serve an additional purpose which will be explained later.

In normal operation the employee inserts his card in card receptacle 16, then pushes down the handle 17, whereupon hammer 18 is actuated and the time printed on the card by clock-controlled type wheels indicated at 19, printing through ribbon 20, the upper portion of which is blue and lower portion red.

Position of the printing ribbon is controlled by mechanism fully described in the copending application of C. E. Larrabee, Serial No. 3,574, filed January 20, 1925. Suffice to say here that it comprises, in part, clock-actuated star wheel 21 controlling bell crank 22 which is pivoted at 23 and carries pins 24 and 25 engaging said star wheel, also carrying pin 26 engaging vertical slotted member 27; lever 28 pivoted at 29; link 30; arm 31 pivoted at 32; and arm 33 also pivoted at 32 and supporting a vertical framework 34 which controls the ribbon.

Whenever handle 17 is depressed, during the first part of the travel the downwardly projecting arm 35 moves link 36 to the right and this link in turn moves to the right downwardly projecting arm 37 of bell crank 38 pivoted at 39 and supporting at pivot 40 the above mentioned slotted vertical member 27 which is therefore moved vertically every time handle 17 is actuated. Although member 27 moves in a substantially vertical path, that path varies in detail according to position of pin 26, position of which in turn is determined by position of bell crank 22. In the position shown, shoulder 37 on member 27 will on every up stroke engage the left hand end of lever 28 which will be rotated clockwise and through the mechanism already described will raise the ribbon so the printing, which occurs at the end of the stroke of handle 17, will take place through the lower half of the ribbon. If pin 26 is in its other position due to bell crank 22 having been shifted to the right by star wheel 21, then member 27 will be inclined to the right sufficiently so that shoulder 37 will clear lever 28 while shoulder 41 will engage the right hand end of 28, resulting in arms 31 and 33 being held down and printing will

take place through the upper half of the ribbon.

In carrying out my invention I introduce arm 45 pivoted at its rear end to a rigid bracket at 46 and resting near its front end on the cross member 47 of ribbon frame 34 against which it is held resiliently by spring 48.

Pivoted at 49 on vertical fixed plate 50 is a cam plate 51 having an arm 52 extending to the left and from arm 52 a downwardly extending projection 53 to the bent lower end of which is secured a spring 54 by which the upper edge of arm 52 is normally held resiliently in contact with the front end of arm 45. Cam plate 51 on its upper edge has a high arcuate section 55 and a lower arcuate section 56. Additional support and guidance for cam plate 51 is provided by stud 57 secured to fixed bracket 58 and passing through slot 59 in plate 51. During normal operation, while printing with the blue ribbon, arm 45 is down, arm 52 is held down thereby and cam plate 51 is in the position indicated by full lines in Fig. 2 with the low portion of its upper edge directly underneath manual lever 17, permitting manual lever 17 to be operated in an ordinary manner.

Whenever the recorder is printing red, however, arm 45 is in raised position and by means of spring 54 has carried with it arm 52 so that cam plate 51 now occupies the position indicated by dotted lines in Fig. 2 with the high portion of its upper surface directly underneath handle 17 so that 17 can be depressed only enough to operate the ribbon shift, but not enough to actuate the printing device so the recorder is inoperative. If now key 15 be inserted and hook

12 turned clockwise to dotted position (Fig. 2), then arm 52 will be lowered and cam plate 51 restored to its normal position so that handle 17 and the recording mechanism may be fully operated.

When the key is turned in reverse direction arm 52 will again rise, cam plate 51 will move to its dotted position and the recording mechanism will again be in non-operative condition and will remain so until the key is again turned or until the normal operation of the ribbon shift device again places the recording mechanism in operative condition.

I claim:

1. In a time recorder, in combination with a handle for effecting recording operations, multi-color ribbon controlling mechanism, means operative upon the shifting of said ribbon mechanism for locking said printing handle against operation, and supplementary means for unlocking said handle when so locked.

2. In a time recorder, in combination with an operating handle for effecting recording operations, means under the control of the clock mechanism for automatically locking said handle, and supplementary key operated means for temporarily unlocking said handle to permit the making of a late registration.

3. In a time recorder, in combination with a handle for effecting recording operations, means for locking said handle against operation to prevent the making of a late registration, and a key operated means having provisions for releasing said locking means when held in shifted position.

In testimony whereof I hereto affix my signature.

SEWARD E. SWICK.
